UNITED STATES PATENT OFFICE.

FRED D. PARKER, OF DENVER, COLORADO.

WELL-DRILL.

SPECIFICATION forming part of Letters Patent No. 295,045, dated March 11, 1884.

Application filed November 2, 1883. (No model.)

To all whom it may concern:

Be it known that I, FRED D. PARKER, a citizen of the United States, residing at Denver, in the county of Arapahoe and State of Colorado, have invented certain new and useful Improvements in Well-Drills, of which the following is a specification, reference being had therein to the accompanying drawings.

This invention relates to certain improvements in well-drills; and it has for its objects to provide a drill which will cut rapidly, and which will permit the débris or portions disintegrated to rise readily above the cutting-edge of the drill, so as not to interfere with the work, as more fully hereinafter specified.

This invention further has for its object to provide for conveniently removing the débris or core cut by the drill from time to time.

These objects I attain by the means illustrated in the accompanying drawings, in which—

Figure 1 represents a perspective view of my improved drill, and Fig. 2 a view partly in elevation and partly in section of my improved device for removing the débris or core left by the drill.

In the drawings, the letter A indicates a metallic tube, which is slotted diametrically on opposite sides near its lower end, as shown in Fig. 1 of the drawings. The lower edges of the drill are serrated, or formed with teeth B, so as to cut into the material at each drop of the said drill. The drill at its upper end is provided with the usual bail, C, to which the rope or chain by which it may be operated is attached.

In Fig. 2, the letter D indicates a tube of the same size as the drill before mentioned diametrically. The lower end of the said tube, however, is not serrated, but at one side is provided with a slot or opening, E, through which is looped a wire, F, which is also looped around one side of an annulus, G, of the same

diameter as the said tube D, forming a hinged joint for the two parts.

The tube D, like the drill-tube, is provided with a bail at its top, to which may be attached the rope or chain for operating it.

The operation of my invention will be understood in connection with the above description, and is as follows: The drill-tube is lifted and dropped in the usual manner, the serrated edges cutting into and through the rock or soil to be bored. The longitudinal slots permit the débris or substance removed to rise freely out of the way, so as to give the drill free working room. When the drill has bored a certain distance, and further work becomes impracticable on account of accumulated material, the drill is removed and the tube D is inserted in the bore. The hinged annulus drops over the upper end of the core cut out by the drill, and upon lifting the said tube D the annulus falls at an angle, so as to grasp the core and carry it up with it, removing it from the well.

Having thus described my invention, what I claim, and desire to secure by Letters Patent, is—

1. A drill-tool constructed of a single piece of tubing of suitable diameter, having diametrical slots at the lower end, leaving downward extensions, which are provided with a series of cutting-edges at their lower ends, substantially as specified.

2. A device for removing the débris from wells drilled or bored as described, consisting of a tube corresponding in size diametrically with the drill-tube, and having a hinged annulus at its lower end, adapted to operate substantially in the manner specified.

In testimony whereof I affix my signature in presence of two witnesses.

FRED D. PARKER.
